UNITED STATES PATENT OFFICE.

MARTIN A. ERICKSON, OF DEER RIVER, MINNESOTA, ASSIGNOR OF ONE-HALF TO OWEN E. HULEHAN, OF DEER RIVER, MINNESOTA.

WINDOW-DRAPERY SUPPORT.

1,250,823.

Specification of Letters Patent. Patented Dec. 18, 1917.

Application filed December 1, 1916. Serial No. 134,454.

To all whom it may concern:

Be it known that I, MARTIN A. ERICKSON, a citizen of the United States, residing at Deer River, in the county of Itasca and State of Minnesota, have invented certain useful Improvements in Window-Drapery Supports, of which the following is a specification, reference being had therein to the accompanying drawing.

10 This invention relates to supports for draperies, such as window shades, portières, curtains and the like, and the primary object thereof is to provide a bracket which may be readily applied to the window frame and easily removed therefrom.

Another object of the invention is to provide a drapery support which may be applied to the window frame without the employment of special fastening devices or indeed any fastening device other than that forming a part of the device.

It is also the purpose of my invention to provide means whereby the distance between the two shade brackets may be adjustable 25 to compensate for varying widths of window frames.

I have also provided means for conveniently supporting a curtain pole or portière pole which may be folded or swung 30 against the frame when not in use.

The invention is clearly illustrated in the accompanying drawings, in which:—

Figure 1 is a perspective view of the window frame to which the invention is applied;

Fig. 2 is an enlarged sectional detail taken on line 2—2, Fig. 1;

Fig. 3 is a fragmentary end elevation of the invention.

40 Referring now to the drawings by numerals of reference, 1 designates a window frame of usual construction, to the upper rail of which I prefer to attach the support. The support is shown as consisting of a bar

45 2, the intermediate portion of which is provided with bent over edges 3 and 4 to form a guide groove for the reception of a longitudinally movable shade bracket 5. One end of the bar is bent at right angles to the body

50 portion, to form a flange 6 for engagement with the outer side edges of the vertical rail of the window frame, and at the intersection of the flange 6 with the body portion

of the bar the said bar is bent in the form of a socket or barrel 7 for the reception of 55 the vertical arm 8 of a curtain or portière-pole bracket 9, said bracket having a laterally extending portion 10 and an upwardly extending terminal 11.

The relation of the arm 8 with respect to 60 the socket or barrel 7 may be such that the portions 10 and 11 of the pole support may be swung against the face of the window frame when not in use. I may, however, construct the pole bracket in such manner 65 that it will be held rigid to said bar. At the end of the support distant from the flange 6 is a spring clamp holding barrel 12 to engage the intermediate portion of the spring clamp 13. This clamp is shown near 70 its end as provided with coils or convolutes 14 and 15 and with terminal spurs 16 and 17 adapted to engage the upper and under faces of the top rail of the window frame, while the flange 6 abuts against the 75 outer edge of the vertical rail of said window frame. Of course it is understood that there will be two of the supports, one at each upper corner of the window frame, and that one shade bracket will be provided with 80 a hole or opening and the other with a slot, in the usual manner.

When it is desired to apply the support it will be only necessary to position it so that the flange 6 abuts against the outer edge of 85 the side rail and the spring, actuated spurs 16 and 17 engage the upper and lower edges, respectively, of the top rail so that the support will be held rigid with respect to the frame.

In the event that the spring portions 14 and 15 are insufficient to cause an adequate engagement of the spurs 16 and 17 with the frame, said spurs may be inserted into the wood by pressing upon the same with the 95 thumb or otherwise. Ordinarily, however, this will not be necessary.

When it is desired to remove the fixture it will be only necessary to remove the spurs from engagement with the top rail, where- 100 upon the fixture may be removed.

From the foregoing it will be apparent that I have provided a shade, portière or curtain fixture which may be expeditiously applied and easily removed from its sup- 105 port without perceptible marring of the

frame and without the necessity of employing additional fastening means of special tools.

Having thus described my invention, I
5 claim:

1. A fixture of the class described comprising a support including a bar, a flange extending at right angles from one end of the bar, a bracket mounted on the bar, a
10 barrel formed at the opposite end of the bar, and a vertical spring clamp mounted in the barrel and formed from a single piece of wire including an intermediate portion engageable in the barrel, spring coils
15 formed near the ends of the wire and rail engaging terminals at the ends of the wire.

2. In a fixture of the class described a support formed from a single piece of sheet metal consisting of a bar, a rail engaging flange extending at right angles from one end of the bar, a barrel formed at the point of juncture of the flange and the bar and adapted to receive a pole-carrying bracket, guide flanges formed on the upper and lower edges of the bar and adapted to receive the shade bracket and another barrel formed on the opposite end of the bar and adapted to receive the rail clamping means.

In testimony whereof I affix my signature.

MARTIN A. ERICKSON.

Copies of this patent may be obtained for five cents each, by addressing the "Commissioner of Patents,
Washington, D. C."
